CLAIM

The ornamental design for a bottle, as shown and described.

DESCRIPTION

FIG. 1 is a side elevational view of a bottle showing our new design, the side opposite being identical to the side shown;

FIG. 2 is a top plan view thereof;

FIG. 3 is a side elevational view rotated 90 degrees from FIG. 1, the side opposite being identical to the side shown; and,

FIG. 4 is a bottom plan view thereof.

FIG.1

FIG.2

FIG.3

FIG.4
